UNITED STATES PATENT OFFICE.

CARL G. NAYLOR, OF CHICAGO, ILLINOIS.

MILL FOR ROLLING FLANGES.

1,276,397.

Specification of Letters Patent. Patented Aug. 20, 1918.

Application filed August 24, 1917. Serial No. 187,930.

To all whom it may concern:

Be it known that I, CARL G. NAYLOR, a citizen of the United States, residing at Chicago, in the county of Cook and State of Illinois, have invented certain new and useful Improvements in Mills for Rolling Flanges, of which the following is a specification.

My invention relates to improvements in mills for rolling flanges.

One of the especial objects of my invention is to provide a mill that will produce a flange, such as a pipe flange, from a ring of ductile material, such as soft iron or steel, by turning an axially disposed part of the ring into radial planes at substantial right angles to the axis of the ring.

Another object of my invention is to provide a mill that will roll the flange so produced to uniform thickness after it has been turned out from the ring into the desired plane.

Another object of my invention is to provide a simple and cheaply to construct mill capable of rapid manipulation and having a large capacity of output.

Other, further and more specific objects of my invention will become readily apparent, to persons skilled in the art, from a consideration of the following description when taken in conjunction with the drawings, wherein:—

Figure 1 is a plan view of the mill.

Fig. 2 is a central longitudinal section taken on line 2—2 of Fig. 1.

Fig. 3 is an end elevation showing the front edge of the mill.

Fig. 4 is an enlarged plan view of the face plate or chuck-bearing table showing parts of the flange chuck, in section.

Fig. 5 is a section taken on line 5—5 of Fig. 2.

Fig. 6 is a vertical central section similar to that shown in Fig. 2, with the parts in different positions.

Fig. 7 is a section taken on line 7—7 of Fig. 6.

In all the views the same reference characters are employed to indicate similar parts.

In the selected embodiment of my invention the frame bed 10 is rectangular in plan, supported by side frame housing members 11 and 12. The side members are provided with legs 13 to support the mill. A cross frame member 14 ties the side frame mem-

bers 11 and 12 together, secured thereto, as at 15 and 16. Another cross member 17 ties the side members 11 and 12 together, being connected to the upwardly extending pillars 18 and 19, as at 20 and 21, respectively. The 60 cross member 17 carries a shaft bearing 22 for the power shaft 24. Another bearing 25, for the shaft 24, is provided upon the upper end of a vertical frame leg 26, which is provided with an inwardly and horizontally 65 extending member 27 that is bolted to the cross member 14, as at 28. The power shaft 24, which is rotatably mounted in the bearings 22 and 25, carries two driving, clutch pulleys 30 and 31. These pulleys, as usual, 70 are loose upon the shaft 24, but capable of being connected thereto, alternatively, by the friction clutches 32 and 33, respectively, when the intermediate clutch member 35 is shifted axially on the shaft 24, for the purpose. The clutch pulley 30 is to be driven in one direction by a belt, not shown, and the pulley 31 in like manner is to be driven in the opposite direction. By this arrangement the shaft 24 may be rotated in either 75 80 direction by selective operation of the clutches 32 and 33. The shaft 24 bears on its out-board end a geared pinion 36 which is in driving mesh with the gear wheel 37. The gear wheel 37 is secured to a shaft, 85 which finds support in the bearing 39 projecting laterally from one side of the leg 26, and in the bearing 40 located upon the upper portion of the cross frame member 14. A geared pinion 41 is loosely mounted on the 90 shaft 38, and is adapted to be connected to and disconnected therefrom by the clutch 42, when the clutch operating member 43 is shifted on shaft 38, for the purpose. A shaft 44 is supported on frame 10 in bearings 45, 46 95 and 47 and on its rear outboard end it carries a gear wheel 48 that meshes with the gear pinion 41. Secured to the shaft 44 and located between the bearings 45 and 46 is a worm 49. A segment 52 of the worm wheel 100 50 is in meshing driving relation with the worm 49. The geared disk segment 50 is provided with a stub shaft 51 which is concentric with the toothed portion 52 of the segment. On the opposite side of the mill 105 is another shaft 44' and supports, which are similar in every respect to the shaft and the parts just described. These parts are indicated by the same reference characters with the addition of the exponent prime (').

The stub shafts 51, 51' find support in the bearings 53, 53' that are parts of the side frame members 11 and 12, respectively.

A yoke, or arm 55, has its ends 56 and 57 connected to one side of the axis 51 of the worm disk segment, respectively, as at 58. A bearing sleeve 59 is slideable in a bore 60 made through the apex of the arm 55. The sleeve 59 carries a rotatable arbor, or shaft, 61, which carries on one end a flange-engaging roller 62, and on the other end a boss or head 63. The sleeve 59 is longer than the width of the arm 55 so that the roller 62 may be moved axially, either in a horizontal or vertical direction, depending upon the position of the arm 55.

When the arm 55 is rotated, upon its stub-shafts 51-51' by the operation of the worms 49-49' in engagement with the worm wheel segments 52-52', the outer edge of the roller 62 will be bodily moved around the axis of said stub shafts.

A bed or plate 70 is slideable in the guide ways 71 and 72, provided on the rectangular base frame 10. Bearing boxes 73 and 74 are fixed to the bed 70, as by bolts 75, or otherwise, and provide alining bearing supports for the front end of the shaft 38. A spline 76 is made into the front end of the shaft 38 and a beveled pinion 77 is located between and rotatably supported by the bearings 73 and 74, which are slideable upon the shaft. The pinion is driven by a feather 79, carried by the pinion, and axially movable in the spline 76.

The slideable plate 70 extends upwardly, as at 79', to provide a hollow boss or hub to receive a vertically disposed sleeve 80. Mounted on the sleeve 80, and secured thereto by a key way 81, is a beveled gear wheel 82, which meshes with the beveled pinion 77, driven by the shaft 38. It will be observed that the ends of the pinion 77 are rotatably supported in the bearings 73 and 74, so that should the shaft 38 be withdrawn from the pinion 77 it would be held in alinement by the bearings provided in the boxes 73 and 74. The upper surface 83, of the beveled gear 82, provides a face plate or chuck-receiving table, upon which is supported a flange-engaging chuck 84. The table 83 is slotted at intervals, as at 85, to provide for emplacement of relatively larger or smaller chucks than that shown in the drawings, which are to be held on the face plate by bolts 86 that pass through the slots 85. The chuck 84 is provided with an annular concentric depression, within which is seated an annular replaceable wearing ring 87, having an inner diameter substantially the same as the outer diameter of the flange sleeve or ring 88. A radially divided, tapered annular chuck member 89, shown in Fig. 4 to contain four separated parts, are yieldingly held together by a

coiled spring ring 90, which is seated in a groove extending around and in the said parts of the inwardly-tapered chuck ring. Seated in the plural part tapered ring 89, is a reversely tapered disk 91 which is secured at its axis to a vertically extending arbor 92. When the vertically disposed arbor 92 is moved downwardly, carrying the tapered chuck disk 91 with it, the latter will expand the tapered chuck ring 89 into more intimate contact with the inner surface of the flange ring 88 against the wearing ring 87 of the chuck, thereby holding the flange ring firmly in the position in which it has been placed in the chuck. The lower end of the stem or arbor 92 is threaded, as at 93 for a nut 94. The nut is freely rotatable around the arbor 92, and is prevented from leaving the end thereof by the annular perforate plate 95. Surrounding this nut is a friction brake band 96, having its opposite ends 97 and 98 connected to two vertically disposed parallel rotatable arbors 99 and 100, respectively. These arbors bear upon their upper ends intermeshing gears, or pinions 101 and 102, respectively. A handle or arm 103 extends forwardly and is employed for rotating the arbors 99 and 100 to tighten the brake band 96 around the nut 94.

The chuck 84 is provided with a vertically movable bottom plate 84' which carries on its outer peripheral edge a stop ring 87' upon the upper edge of which rests the flange ring 88 when it is placed within the chuck 84. The thickness of this ring 87' will determine the extent to which the ring 88 will project above the chuck, and serves as a means for ejecting the ring 88 from the chuck when the flange has been formed.

The vertically movable stem 92 is provided with a reduced portion 92' that passes neatly through the plate 84 into the disk 91. When the stem 92 is raised the shoulder 92' will engage the plate 84' and raise it and the flange 88 so as to substantially eject the latter from the chuck. The operation of the chuck and flange ejector will be more fully hereinafter explained.

Rotatably supported on the cross frame member 14 is a threaded shaft 105. The shaft is in threaded engagement with a depending lug, 106 which is secured to the bottom of the plate 70, as by bolts 107. A sleeve 108 is loosely rotatable upon the shaft and carries a sprocket wheel 109 and a friction disk clutch member 110. The sleeve, disk and sprocket wheel are driven by the sprocket chain 111, from a sprocket wheel 112 secured to the shaft 38. Another sleeve 113 is fast upon the shaft 105 and is axially movable thereon by a clutch-operating lever 115, to bring the disks 110 and 114 into friction engagement and driving relation,

Extending across the front of the mill and near the bottom thereof a clutch operating shaft 116 supported in brackets 117 and 118 extending from the base plate 10.

5 A clutch-shifting lever 119 is secured to the shaft 116, as by a pin 120, so that when the lever 119 is moved, the shaft 16 is rocked. Another clutch operating lever 121 is loosely supported on the shaft 116, and has an extended end 122 therebelow, which is pivotally connected to a rearwardly extending rod 123. This rod is pivoted, as at 124, to a transversely extending arm 125 which is secured to the upright shaft 126, that has bearing in brackets 127 and 128. An arm 129 is secured to the vertical shaft 126, as by a key 130, and is pivotally connected to the axially movable clutch shifting member 35.

20 An arm 132 is secured to the shaft 116, as at 133, and is pivoted to a reciprocatable rod 134 that is supported in brackets 135 and 136, the rear end of which is pivoted, as at 137, to an upwardly extending lever 138.

25 This clutch shifting lever 138 is pivoted to the frame, as at 139, the upper end of which, 140, engages the axially movable clutch element 43 to connect and disconnect the clutch 42 with the pinion 41. The arm 30 55 is provided with a V-shaped notch 141, which communicates with the bore 60 in which the sleeve 59 is axially movable. The sleeve 59 is provided with a rack 142, on one side, into which meshes a geared pinion segment 143 which is, preferably, part 35 of the lever 144, and which is pivoted as at 145, to a pin 147, to retain the geared segment in mesh with the rack. The lever 144 bears on its outer end, a head 148, through 40 which passes an operating pin 149. The pin bears a flange 150 against which presses an open helical spring 151 to press with some yielding effect the end of the pin 149 against the inside surface of the flange 152.

45 The flange 152 is bored, as at 153, and 154. The bore 153 is shown in Fig. 6, but the pin 149 covers the opposite bore in the flange 147 in which the pin is now located. When the pin 149 is in the bore 154, as shown in 50 Fig. 6, the sleeve 59 has been moved out of the bore 60 to its farthest extent by operation of the geared segment 143 in co-operation with the rack 142 and when the arm 144 is turned to the left, the geared segment 55 143 in co-operation with the rack 142 will move the sleeve 59 back into position so that the roller 62 may be raised or lowered when its axis is in a vertical plane.

55 The rod 160 for operating clutch 110—114, 60 passes through ears 161 and 162 projecting from the sides of the base plate 10 and is pivotally connected to the upwardly extending hand lever 163. The lever 163 is provided with a heel piece 64 which normally bears on the front surface of the ear

161 and holds the handle 163 in an upwardly inclined position. The inner end of the rod 160 is connected to a clutch operating lever 164 that is pivoted, as at 165, and has an inwardly extending end 166 that slides 70 the clutch member 114 into contact with a similar member 110 on the shaft 105 to drive this screw shaft when the lever 163 is depressed.

75 The operating of the mill is substantially as follows:—The clutch operating lever 121 is pulled outwardly and this rotates the shaft 126 and causes the arm 129 to move the clutch-operating member 35 into association with the clutch 33, thereby connecting the clutch pulley 31 to the shaft 24. This causes the pinion 36, fixed to the shaft 24 to rotate the gear wheel 37 which is secured to the shaft 38. Now the sleeve 108 surrounding the shaft 105 is being rotated 80 by the shaft 38 through the instrumentality of the link belt 111 and its associated sprocket wheels. Pressure is now applied to the upper end of the hand lever 163, which moves the friction disk 114, rotatably secured to the shaft 105, to make driving contact with the friction disk 110, which is driven by the sprocket belt 111, thereby rotating the screw 105 and moving the table 70, and supported parts, outwardly, upon its 85 ways 71. The bearing boxes 72 and 74, and the pinion 77, move outwardly with the bed 70 and these parts do not leave, entirely, their engagement with the shaft 38. As the spline 76 is cut to the end of the shaft 38, 90 the feather 79 will move therein and the pinion will remain in rotative engagement with the shaft through the feather 79 and will be supported in alinement by the bearing boxes 73 and 74, if the shaft 38 was entirely withdrawn. When the table 70 moves outwardly, it carries with it the face plate 83, and the chuck 84 which is secured on the working surface thereof. It is now desirable to raise the sleeve 59 so as to lift the 105 roller 62 above the chuck 84 to facilitate the removal of a flange and the emplacement of a ring 88 in the chuck. The pin 149 is then pulled outwardly until it leaves the perforation 154 in the flange 152, after which the 110 arm 144 is moved over until the pin is in register with the perforation 153 in the flange. This will rotate the pinion 143, that is in mesh with the rack 142, and lift the sleeve 59, together with the roller 62. 115 A new sleeve 88, of which a flange is to be made, is now inserted in the chuck and the lever 103 is grasped so as to draw the brake band 96 tightly around the screw nut 94. This will frictionally engage the nut and hold it still while the sleeve 80 and stem 92 are being rotated. The nut, by this operation, will pull down the stem 92, upon the upper end of which the tapered chuck disk 91 is secured, thereby causing the disk 130 120

to press the divided members of chuck ring 89 outwardly into firm engagement with the ring 88, of which a flange is to be made. The plate 84 and stop ring 87 will be in positions shown in Fig. 2 when the shoulder 92' is below the upper surface of the work table 83. The sleeve or ring 88 is placed in the chuck with its lower edge resting on the stop ring 87 and the plate 84 in its lowermost position. The chuck may then be closed by pressing the disk 91 firmly into contact with the chuck member 89 as heretofore described.

The chuck-operating lever 121 is now moved in the opposite direction, whereupon the pulley 30 is connected to the shaft 24 through the instrumentality of the friction clutch 32 and the pulley 31 is disconnected therefrom. This will rotate the shaft 24 in opposite direction and consequently it will rotate the shaft 38 in the opposite direction. Now if pressure is again applied to the lever 163 the clutch members 110 and 114 are brought into connection and the screw 105 is rotated in direction reverse from its former operation, thereby causing the table 70 to be returned to its operative position. It is assumed that the arbor 61 and the roller 62 are now substantially in the position shown in Fig. 2, with the exception that they have been elevated by the depression of the arm 144. Now the arm 144 is moved back to the position shown in Fig. 2, which has the effect to lower the roller 62 to the proper position to engage the inner surface of the ring 88, of which the flange is to be made. So soon as the clutch operating lever 163 is released, the friction disks 110 and 114 will no longer be held in sufficient contact to rotate the screw shaft 105 and therefore the table may be stopped at any position desired in its forward and backward movement, by simply releasing the handle 163. Now when the clutch lever 119 is moved outwardly, this will push the rod 134 rearwardly, causing the end 140 of the lever 138 to move the clutch shifting lever 43 so as to cause the friction clutch 42 to connect the pinion 41 of the shaft 38. This will rotate the shafts 44, 44' thereby rotating the geared segment disks 50—50' so that their top surfaces will be carried to the right, as viewed in Fig. 2, and as shown in dotted lines in Fig. 6. The shaft 38, now rotating, causes the beveled geared pinion 77 to rotate the gear wheel 82, upon which the chuck 84 is mounted, and thereby the ring 88, of which a flange is to be made. The roller 62 contacts the flange ring 88 just above the upper surface of the chuck 84, and thereabove, presenting maximum surface engagement, and as the roller 62 is bodily moved around the axis 51, upon which it is rotated, the upper surface of the ring 88 is thereby deflected outwardly, as shown in Fig. 6, until the axis of the roller

62 is substantially in a horizontal plane, in which event the two members of the flange 88 are in planes at substantial right angles to each other. The horizontal portion of the flange 88 may now be rolled between the 70 roller 62 and the upper surface of the chuck 84 so as to make a uniform cross section thereof.

When the shaft 38 is rotated in one direction the segments 52, 52' are rotated in such 75 direction as to cause the roller 62 to be bodily moved to a position with its axis in a vertical plane, and while this movement is progressing the direction of rotation is proper to rotate the screw shaft 105 to move 80 the table 70 outwardly, from its operative position, to more easily remove the finished flange from the chuck, in which it has been secured and the rotation of the table 83 is then such that the application of the brake 85 band 96, by pressure upon the lever 103, tends to loosen the nut 94 on the lower end of the stem 99 and permit disengagement of the clutch members 89 and 91 to facilitate removal of the finished flange, which is practically ejected from the chuck by raising of the plate 84'.

While I have herein shown a single embodiment of my invention, for the purpose of clear disclosure, it is manifest to persons 95 skilled in the art that many changes may be made in the general form and arrangement of the parts within the scope of the appended claims.

Having described my invention, what I 100 claim is:—

1. A ring chuck having a fixed annular part to engage the outer surface of a ring; a radially expanding chuck member to engage the inner surface of the ring; a stop, 105 for said ring, to permit a part of the ring to extend outwardly beyond the face of the chuck; a disk having a tapered edge for engaging the inner expandable member of the chuck; a stem secured to the disk to draw it 110 into said expandable member; a nut on the stem; means to manually hold the nut from rotation; means to rotate said chuck member's stem and ring; a roll for engagement with the inner surface of the outstanding 115 part of the ring, and means to rock the roll while the ring is being rotated, to roll the outstanding part of the ring into a substantial radial plane.

2. A flange rolling mill comprising a 120 chuck to receive a ring; a vertically movable, ring-receiving stop within the chuck; a rotatable table to receive the chuck; a part rotatable with the table, to open and close the chuck when its rotation is stopped and 125 an impositive means to stop rotation of the part.

3. A flange rolling mill comprising a 130 chuck to receive a ring; a vertically movable ring-receiving stop and ejector, within the

chuck; a rotatable table upon which the chuck is axially mounted; a part rotatable with the table to open and close the chuck when its rotation is stopped and to vertically move said ejector and means to stop rotation of said part.

4. A flange rolling mill comprising a band-engaging flange-roller having a vertical axis; means for rotating said roller transversely of its axis in contact with the band; a band or ring-holding chuck having a vertical axis about which it is rotatable while holding the band in contact with the roller; means for rotating the chuck; means for bodily moving the chuck forwardly out of working position while rotating, and means for automatically disengaging the flange after its bodily movement has begun.

5. A flange rolling machine comprising a flange roller having a normal vertical axis; means for bodily moving the roller to a position with its axis in a substantially horizontal plane; a band-receiving chuck having its axis in a vertical plane; means to rotate the chuck in a given direction while the roller is turning the flange on the band; power means to tighten the chuck while rotating in said

direction; means to reverse direction of rotation of the chuck to loosen the band and means for bodily moving the chuck away from the roll, accessible for removing the flange and placing another band in the chuck.

6. In combination with a flange rolling machine having a rotatable band engaging chuck and an oscillatable flange roller, of power means to tighten the chuck, manually operable means for controlling said chuck operating means; means to slide the chuck bodily from operative engagement with the flanging roll and means for reversing direction of rotation of said chuck operating means to open the chuck.

7. In a machine of the character described, a band-receiving chuck; power means to close and open the chuck; manual means for controlling the power means; means to rotate the chuck; a flange roller to turn the flange and means to automatically remove the flange from the chuck when the chuck is opened.

In testimony whereof I hereunto set my hand.

CARL G. NAYLOR.
